CLAIM

I claim the ornamental design for a grooming tool, as shown and described.

DESCRIPTION

FIG. 1 is a right side perspective view of a grooming tool according to the present design;

FIG. 2 is a rear perspective view thereof;

FIG. 3 is a left side perspective view thereof;

FIG. 4 is a front perspective view thereof;

FIG. 5 is a bottom plan view thereof; and,

FIG. 6 is a top plan view thereof.
